RELAY FOR ELECTRIC GASEOUS
DISCHARGE LAMPS

Matthew C. Abbott, Ipswich, Mass., assignor to
Hygrade Sylvania Corporation, Salem, Mass., a
corporation of Massachusetts

Application March 28, 1941, Serial No. 385,674

6 Claims. (Cl. 200—122)

This invention relates to electric gaseous discharge lamps and more particularly to starting relays therefor.

An object of this invention is to provide a starting relay which will permit an immediate starting of the heating cycle with respect to the electrodes of the lamp.

Another object is to provide a fast closing of the heater circuit on the restart cycle.

A further object is to provide a thorough heating cycle for lamp electrodes.

Other objects, advantages and features will be apparent from the following specification, taken in conjunction with the accompanying drawing in which:

Figure 1 is a top view of the relay showing the elements as they appear in a dead circuit equilibrium position.

Figure 2 is a top view of the relay showing the elements as they appear just after the initial starting cycle and during the lamp operating position.

Figure 3 is a top view of the relay showing the elements as they appear when the auxiliary starting feature of the relay operates.

Figure 4 is a side elevational view of the relay.

Figure 5 is a schematic diagram of the circuit in which this relay may be used.

Generally speaking, two different types of relays are used in the auxiliary starting equipment for electric gaseous discharge lamps. One is a thermal and the other is a glow switch. One of the main disadvantages of the glow type of relay is that it is usually necessary for the relay itself to heat up before the filamentary electrodes of the lamp start to receive any heat. This pre-heating period is really time lost. In the thermal relay, no preheating in the relay is necessary before the filamentary electrodes start to heat but the restarting time is too long. In the thermal relay, the bimetallic strip or other expanding element must cool down before restarting can be attempted.

I have, therefore, devised a relay which combines the better features of both types and eliminates the less desirable characteristics. The relay of my invention combines the quick starting ability of the thermal and the quick relighting feature of the glow.

Figure 4 shows the sealed container 1 with the base 2 and the base pins 3, 4, 5 and 6 extending therefrom. The vent 7 in the stem 8 provides for the exhausting of the container 1 and the filling thereof with an inert gas such as neon at a low pressure for example 8 mm.

The lead-in wires 9 and 10 serve as supports for the bimetallic strips 11 and 12 respectively. The lead-in wires 13 and 14 serve as supports for the filament 15 which acts as the heating unit.

Figure 5 shows how the relay may be connected with an electric gaseous discharge lamp. The lamp 16 has the alkaline earth oxide-coated filamentary electrodes 17 and 18 sealed at the ends thereof. One end of electrode 17 is connected directly to the line. The other end of electrode 17 is connected to one end of electrode 18 through the relay 1. The other end of electrode 18 is connected to the line through the resistance 19 and the ballast impedance 20.

Figures 1, 2 and 3 show the relative location of the various elements of the relay. Figure 1 shows the position which the parts assume under a dead circuit equilibrium condition. The bimetallic strip 11 supported from the lead-in wire 9 is bent around the heating element 15 which is in turn supported by the lead-in wires 13 and 14. The free end of this strip 11 has the contact 21 attached thereto. This contact 21 touches the contact 22 on one side of the fixed end of bimetallic strip 12, the other side of this end of the strip being fixed to the lead-in wire 10.

When the circuit is connected to the line, the filament 15 will heat very rapidly. The heat given off by this filament will heat the bimetallic strip 11 until it has been distorted sufficiently to break away from its contact with bimetallic strip 12. Strip 11 is formed in such a manner that its free end will create a tension sufficient to permit the necessary heating of the filamentary electrodes 17 and 18 of the lamp 16 before the heat from the heating element 15 becomes sufficient to cause the strip 11 to break away from strip 12.

Figure 2 shows the relationship which the parts assume to each other after the opening of the relay and during the operation of the lamp. The strip 11 has been heated sufficiently to cause its free end to bend away from the fixed end of strip 12. If for some reason, the lamp arc fails to strike or maintain or if the line switch is turned off momentarily, the free end of strip 12 heated by an arc discharge between the strip 12 and the other starting of the relay, closes in on the fixed end of strip 11 to close the starting circuit.

Figure 3 shows the position which the elements assume when the auxiliary starting means is employed. The contact 23 on the free end of strip 12 has now closed the circuit through the contact 24 on the fixed end of strip 11. The

circuit through the relay being closed, the filamentary electrodes 17 and 18 of the lamp 16 are heated. Once the circuit has been closed, the strip 12 starts to cool and is calculated to break from its contact with strip 11 at about the same time that the lamp electrodes have become heated sufficiently to carry the discharge across the lamp. The elements of the relay will then assume the positions as shown in Figure 2. If the lamp arc again fails to strike or maintain, the glow auxiliary will again function to heat the filamentary electrodes of the lamp.

When the lamp arc fails to strike or maintain upon the action of the thermal elements, the circuit voltage across bimetal 12 and the other elements of the switch will cause a glow discharge to be initiated, thereby heating bimetal 12 and causing it to move inward. If as a result of the glow discharge, the lamp lights, the lamp voltage between the bimetal 12 and the other elements of the switch will not be sufficient to cause a continuous glow discharge and the elements of the switch will assume the positions shown in Figure 2.

What I claim is:

1. A relay comprising: a sealed container; an atmosphere of inert gas at low pressure in said container; an electrical contact; a bimetallic strip in closing relationship to said contact; a heating element in heating relationship to said bimetallic strip; a second electrical contact; and a second bimetallic strip open to said second contact but in position to be closed by said second contact by the passage of current through said inert gas.

2. In a relay for preheating the filamentary

electrodes of an electric gaseous discharge lamp, said relay having sealed therein an atmosphere of inert gas at low pressure, the combination: an electrical contact; a bimetallic strip closed to said contact; a heating element in heating relationship to said bimetallic strip; a second electrical contact; and a second bimetallic strip open to said second contact but in position to be closed to said second contact by the ionization of said inert gas after the breaking of said first contact from said first bimetallic strip.

5 3. In a relay for preheating the filamentary electrodes of an electric gaseous discharge lamp, said relay having sealed therein an atmosphere of inert gas at low pressure, the combination: an electrical contact; a bimetallic strip closed to said contact; a heating element in heating relationship to said bimetallic strip; a second electrical contact; and a second bimetallic strip open to said second electrical contact.

15 4. The relay of claim 1 in which said second bimetallic strip is electrically connected to the first-mentioned electrical contact, and the first-mentioned bimetallic strip is electrically connected to said second electrical contact.

5 5. The combination of claim 2, in which said second bimetallic strip is electrically connected to the first-mentioned electrical contact, and the first-mentioned bimetallic strip is electrically connected to said second electrical contact.

30 6. The combination of claim 3, in which said second bimetallic strip is electrically connected to the first-mentioned electrical contact, and the first-mentioned bimetallic strip is electrically connected to said second electrical contact.

35 MATTHEW C. ABBOTT.
